UNITED STATES PATENT OFFICE.

GEORGE JOSEPH CAPEWELL, OF CHESHIRE, CONNECTICUT.

NAIL-EXTRACTOR.

SPECIFICATION forming part of Letters Patent No. 394,756, dated December 18, 1888.

Application filed April 7, 1888. Serial No. 269,938. (No model.)

To all whom it may concern:

Be it known that I, GEORGE JOSEPH CAPEWELL, of Cheshire, in the county of New Haven and State of Connecticut, have invented certain new and useful Improvements in Nail-Extractors, of which the following is a full, clear, and exact description, whereby any one skilled in the art can make and use the same.

My within-described invention relates to the class of nail-pullers that are provided with pointed jaws and a device for hammering the jaws into the material into which the nail has been driven, so that when the device as a whole is tilted to one side the jaws will keep firm hold of opposite sides of the nail and pull it out.

The object of my within improvement is to provide a nail-puller with jaws that will adapt it for use with either the cut nails, that are usually oblong in cross-section, or with the wire nails, that are round in cross-section, the jaws being especially adapted to grasp the shank of the nail firmly without injuring the head, in case there is one on the nail, and with power to remove the nail even when the head has been broken off.

To this end my improvement consists in a nail-puller having a stock or handle, movable grasping-jaws and percussive device, and the peculiar clamping-lever pivoted to the lower end of the stock.

It further consists in the combination of the stock or handle, the percussive device, and the peculiar grasping-jaws; and it further consists in details of the several parts and their combination, as more particularly hereinafter described, and pointed out in the claims.

Referring to the drawings, Figure 1 is a side view of a nail-puller embodying my invention. Fig. 2 is a detail view of the lower part of the nail-puller with the stop cut in section to show the construction and arrangement of the jaw-lever and the jaws. Fig. 3 is a detail view, in central section, of the lower part of the stock, showing the position of the parts when a nail is nearly drawn. Fig. 4 is a detail view in section of the hammer-stop.

In nail-extractors of the class to which my within-described invention relates the jaws borne in the device are driven into the wood into which a nail has been embedded with an

edge lying on opposite sides of the nail, and the nail-extractor as a whole is pulled side-
wise, rocking upon a foot or lever-arm, and 55 thus holding the jaws tightly closed upon the nail, so that a continued pull will draw the nail out of the material into which it has been driven. It is evident that with a given length of handle the nearer the bearing-point of the 60 foot that forms the fulcrum can be brought to the nail or center of the jaws the greater will be the leverage that can be obtained in the beginning of the operation of withdrawing the nail, and my improved nail-puller, as 65 within described, is constructed and arranged so as to secure the greatest advantages in this regard, and with special reference to obtaining a secure grasp upon the nail near the head, a powerful pull at the beginning of the 70 operation, and a quicker action as the nail is coming out of the wood.

In the accompanying drawings, the letter *a* denotes the stock, that is preferably made of metal cast to shape and in form of a flattened tube or with a lengthwise channel, in which is located a sliding bar or hammer, *b*, that is the percussive device by means of which the jaws *c d* are driven into the material in which the nail is held and from which 80 it is to be drawn. On the upper end of this bar is formed a handle, *b'*, and in order to prevent the accidental withdrawal of the hammer from the channel in which it travels the spring-stop *e* is arranged near the top of the 85 stock, with an end projecting into the channel in such position as to engage in the stop-socket *e'*, that may be a notch cut into the adjacent side of the hammer or bar. At the foot of the stock, and with their ends in the 90 path of movement of the hammer and so as to be moved by it, are secured the jaws *c d* by pins that pass through the slots *c' d'*, and this arrangement permits a certain lengthwise movement of the jaws in the line of the 95 stock, while limiting the extent of such movement. The edges of the channel in the stock form guides for the backs of the jaws, except where they pass through the slot *f'* in the jaw-lever *f*. The latter is a bent lever with 100 one arm extending along the back of one of the jaws and secured by a pivot or pin to the bottom of the stock, while the longer arm of the lever extends across the bottom of the

stock and upon both sides of the jaws that pass through the slot in the lever, and beyond the jaws the lever is curved downward and then upward, forming the fulerum upon which the whole device is rocked in the operation of drawing the nail. On this fulerum side of the lever there is formed a stop that consists of the hook *g*, formed on the stock, and the shoulder *g'*, formed on the lever, and the contact of these two parts prevents the lever from being swung so far downward as to disengage it from the jaws.

The long bearing of the back of the jaw *d* against the upright arm of the lever is of material advantage in guiding and holding the jaws and in keeping them closed upon a nail.

In order to especially adapt the jaws of the nail-puller to grasp a wire nail that has a round shank or stem, and at the same time to avoid crushing the head of such a nail, the points of the jaws are quite sharply curved or hook-shaped and are fluted on the inside, so that while the jaws grasp the shank of the nail *h* very firmly there is room for the head of the nail to lie between the jaws without being pressed out of shape.

When the nail-puller is in position to draw a nail, as shown in Fig. 2 of the drawings, a bearing is formed against the under side of the jaw-lever at a point quite near the jaws, and, owing to the location of the fulerum so near the weight, (the resistance offered by the nail against drawing,) a powerful leverage is secured that is amply sufficient to start the nail, and the further rocking of the nail-

puller quickly draws the nail as the fulerum changes to a point more distant from the nail.

I claim as my invention—

1. In combination with a stock, a percussive device connected thereto, the jaw-closing lever with the fulerum or bearing, and the lengthwise-moving jaws supported in the path of movement of said percussive device, the said jaws having hook-shaped ends that are sharply curved and are also fluted or concaved on the inside, and grasping-surfaces of the jaws, all substantially as described. 40 45

2. In combination with the stock of a nail-puller, the sliding hammer, the lengthwise-moving jaws held in the path of movement of said hammer, and the jaw-lever having an upright arm pivoted upon one side of the jaws and extending across the jaws and forming on the opposite side a fulerum or bearing, all substantially as described. 50 55

3. In combination with the stock of a nail-puller, the percussive device having a sliding play thereon, the jaws having grasping-points and attached to the stock in the path of movement of the percussive device, the bent jaw-lever having an upright arm forming a bearing for the back of one of the jaws and slotted for the passage of the jaws, and the stop that limits the swinging play of the jaw-lever, all substantially as described. 60

GEORGE JOSEPH CAPEWELL.
